UNITED STATES PATENT OFFICE.

JAMES MOYER AND JOHN C. MORGAN, OF ALLIANCE, OHIO.

GASOLINE-TANK FOR GASOLINE STREET-LAMPS.

SPECIFICATION forming part of Letters Patent No. 359,621, dated March 22, 1887.

Application filed September 9, 1885. Serial No. 176,549. (No model.)

To all whom it may concern:

Be it known that we, JAMES MOYER and JOHN C. MORGAN, citizens of the United States, residing at Alliance, in the county of Stark and State of Ohio, have invented certain new and useful Improvements in Gasoline-Tanks for Feeding Gasoline-Lamps, of which the following is a specification.

Said invention relates to the formation of a supplemental chamber in connection with a tank, and in fixing said tank on trunnions in such manner that said tank may be turned to one side and said chamber filled, as shown by the dotted lines in the drawings, and thus gage the amount of gasoline for a single burning.

Said invention also relates to a means for elevating said tank at one end, so as to empty a portion of the fluid from said chamber, if it be desired to burn at one time less than the full of said chamber.

Referring to the accompanying drawings, Figure 1 is an elevation of a street-lamp with the improved tank attached. Fig. 2 is a cross-section showing the end of said tank. Fig. 3 is a longitudinal section showing said tank and its supplemental chamber.

Like letters refer to like parts throughout the several views.

A is an elevation of an ordinary street-lamp. B is an end elevation showing the improved tank.

C is a supplemental chamber connected with said tank, which is constructed of a proper size for holding sufficient gasoline for a single burning.

D is a tube running from said supplemental chamber to the burner g.

E is a piece firmly attached to one end of said tank and provided with holes, so that said tank may be elevated at one end in order to empty a portion of the gasoline which it would normally contain at a filling.

g is a gasoline-burner.

The said improved tank is provided with a pivot or trunnion at one end, which works in a hole of a projection which extends out from the lamp. The other end, being provided with the part E, turns upon the pin f.

The operation of our invention may be described as follows: The operator takes hold of the stem or tube D and turns the said tank to one side, as shown by the dotted lines h. By this means the said fluid passes through the opening shown at g' and fills said supplemental chamber, when said tube is lowered and said tank brought to its normal position.

What we claim as our invention, and desire to secure by Letters Patent, is—

The combination of the main reservoir provided with trunnions and supports for the same, in which the main reservoir is mounted on said trunnions, a supplemental reservoir connected with the same at or near the top, and a burner and tube connected to the supplemental reservoir.

JAMES MOYER.
JOHN C. MORGAN.
